UNITED STATES PATENT OFFICE.

ALDA F. HAWKINS, OF FORT WORTH, TEXAS.

BATTERY-TERMINAL FASTENING.

1,349,957.

Specification of Letters Patent. Patented Aug. 17, 1920.

Application filed April 5, 1920. Serial No. 371,458.

To all whom it may concern:

Be it known that I, ALDA F. HAWKINS, citizen of the United States, residing at Fort Worth, in the county of Tarrant and State of Texas, have invented certain new and useful Improvements in Battery-Terminal Fastenings, of which the following is a specification.

This invention relates to new and useful improvements in battery terminal fastenings.

It has been customary to fasten the rubber caps or tops on the cells of storage batteries in various ways. It is necessary to make the terminal post of a soft metal such as lead alloy and it is obvious that any kind of a screw-threaded arrangement is more or less unsatisfactory because the threads are inclined surfaces that will soon wear owing to the softness of the metal. The idea involved in this invention is to provide a simple and efficient fastening which will be free from the foregoing objections and which may be quickly applied and used at a low cost.

In carrying out the invention the terminal post is provided with an angular shoulder and a resilient or elastic ring is passed down the post and engaged under the shoulder so as to bear on the top of the cap, thereby holding the cap firmly on the post as will be obvious.

The invention will be more readily understood from a reading of the following specification and by reference to the accompanying drawings, in which an example of the invention is shown, and wherein:

Figure 1 is a side elevation of a portion of a storage battery cell showing the cap fastened on the terminal post in accordance with this invention,

Fig. 2 is a plan view of the same, and

Fig. 3 is a longitudinal sectional view on the line 3—3 of Fig. 2.

In the drawings the numeral 10 designates the hard rubber cap of the cell of an ordinary storage battery which is constructed in the usual manner. The cap has a vertical opening 11 for receiving the terminal post 12 of the usual terminal plate 13, which latter is secured to the battery plates 14, in the usual manner. The cap 10 has a seat 15 in its undersurface surrounding the opening 11 and a packing gasket 16 is received in this seat, and the plates 13 contact with the underside of the gasket. This prevents the

solution from passing out through the opening 11 as will be obvious, of course, providing that the parts are in close contact.

The terminal post 12 is provided with a circumferential groove or recess 17 and an annular shoulder 18 which overhangs the groove and is positioned slightly above the top of the cap 10. The remainder of the post above the shoulder is finished in the usual way. In order to fasten the cap in position a ring 19 of rubber or other elastic material is forced down over the shoulder 18 so as to engage into the groove under the shoulder and bear on the top surface 70 of the cap.

The groove being concaved the tendency of the ring is to work in under the shoulder and thus force the cap downward whereby the gasket 16 contacts with the plates 13 and the cap is firmly fastened on the terminal. The ring may be made of rubber or other suitable material. It is preferable to use material which will be elastic and which will have a high degree of acid resistance. It will be noticed that the groove is considerably wider than the diameter of the ring and extends below the top of the cap, and thus the ring tends to embrace the post and fit snugly under the shoulder and can not be easily displaced. In fact the ring will tend to crowd under the shoulder and around the upper edge of the opening 11, there being a space between the upper edge of the opening 11 and the bottom of the groove 17 so that the ring will tend to work into this space and thus securely hold the parts together.

When it is desired to take off the cap it is merely necessary to pry the ring loose and remove it. The fastening is so simple and inexpensive that a new ring may be used each time the cap is replaced, although the same ring could be used in many instances. The invention is not to be limited to an elastic ring and its scope is pointed out in the following claims.

What I claim, is:

1. In a battery terminal fastening, the combination with a cell cap having an opening, of a terminal post extending through the opening and having a stop element at its lower end to engage beneath the cap, said post extending outwardly beyond the cap and provided with a radially projecting flange spaced from the cap, said post having an annular recess beneath the flange, which

recess increases in radial dimension toward the cap providing a tapered portion upon the post decreasing in diameter toward the cap, and a circumferentially contractible 5 ring adapted to be positioned between the flange and cap and to contact with said tapered portion, said tapered portion causing the ring to move toward the cap.

2. In a battery terminal fastening, the 10 combination with a cell cap having an opening, of a terminal post extending through the opening and having a stop element at its lower end to engage beneath the cap, said post extending outwardly beyond the cap 15 and provided with a radially projecting flange spaced from the cap, said post having a tapered portion beneath the flange which decreases in diameter toward the cap, and a circumferentially contractible element arranged between the flange and cap and contacting with the tapered portion to be moved 20 thereby toward the cap.

3. In a battery terminal fastening, the 25 combination with a cell cap having an opening, of a terminal post extending through the opening and having a stop element at its lower end to engage beneath the cap, said post extending outwardly beyond the cap and provided with a radially projecting 30 flange spaced from the cap, said post having an annular recess beneath the flange, said recess being curved in cross section and having its upper portion increasing in radial dimension toward the cap, and an elastic ring arranged between the flange and cap 35 in contact with the curved wall of said recess, said ring being circular in cross section.

4. In a battery terminal fastening, the

combination with a cell cap having an opening, of a terminal post extending through the 40 opening and having a stop element arranged beneath the cap, said post extending above the cap, a packing arranged between the stop element and cap, a radially extending flange carried by the terminal post near the 45 upper surface of the cap, and a highly elastic circumferentially expansible and contractible ring adapted to be moved into engagement beneath the flange for sealing the 50 opening in the cell cap.

5. In a battery terminal fastening, the combination with a cell cap having an opening, of a terminal post extending through the opening and having a stop element arranged beneath the cap, said post being provided 55 near the upper surface of the cap with a surrounding groove, a packing element arranged between the stop element and the lower face of the cell cap, and a highly elastic circumferentially expansible and contractible 60 rubber ring adapted for insertion within the groove to seal the opening in the cap.

6. In a battery terminal fastening, the combination with a cell cap having an opening, of a terminal post extending through the 65 opening and having a stop element arranged beneath the cap, said post extending above the cap, and provided near the upper face of the cap with a surrounding groove, and a highly elastic circumferentially ex- 70 pansible and contractible ring adapted to be moved into the groove in engagement with said cap.

In testimony whereof I affix my signature.

ALDA F. HAWKINS.
